CLAIM

The ornamental design for a bed frame corner post, as shown and described.

DESCRIPTION

FIG. 1 is a perspective view of a bed frame corner post showing my new design;

FIG. 2 is another perspective view of FIG. 1, showing the bed frame corner post in a state of use;

FIG. 3 is a front view thereof;

FIG. 4 is a rear view thereof;

FIG. 5 is a bottom view thereof;

FIG. 6 is a top view thereof;

FIG. 7 is a left side view thereof; and,

FIG. 8 is a right side view thereof.

The broken lines in FIG. 2 represent environmental subject matter only and form no part of the claimed design.
